FREDERICK N. ROSENSTENGEL, OF DETROIT, MICHIGAN, ASSIGNOR TO SATTLEY COIN HANDLING MACHINE COMPANY, OF DETROIT, MICHIGAN, A CORPORATION OF MICHIGAN.

COIN-GAGE FOR COIN-CONTROLLED MECHANISM.

1,158,722.

Specification of Letters Patent.

Patented Nov. 2, 1915.

Application filed January 10, 1913. Serial No. 741,183.

To all whom it may concern:

Be it known that I, FREDERICK N. ROSENSTENGEL, a citizen of the United States of America, residing at Detroit, in the county 5 of Wayne and State of Michigan, have invented certain new and useful Improvements in Coin-Gages for Coin-Controlled Mechanism, of which the following is a specification, reference being had therein to 10 the accompanying drawings.

The invention relates to coin controlled apparatus and has for its object the prevention of the operation of said mechanism by an undersized coin. The device is particularly adapted for use in conjunction with 15 coin counters, and in the specific construction shown effects the locking of the counting mechanism whenever an undersized coin is in engagement therewith.

20 In the drawings: Figure 1 is a longitudinal section through a portion of a coin counting machine to which my improvement is applied. Fig. 2 is a plan view thereof; and Figs. 3 and 4 are views similar to Fig. 25 1, showing the operation of ejecting a coin.

A is a coin feeding tube or conduit into which the coins are introduced by a suitable sorting mechanism not shown. This sorting mechanism is of such a character that the 30 coins are graded as to size; but it sometimes happens that a small coin will be carried by a larger coin and thus find access to the tube A.

B is a counter actuating-wheel, which, as 35 shown, is provided with a circumferential series of concave pockets C adapted to receive coins of the proper dimension or size.

D is a reciprocatory plunger for transferring a coin from the bottom of the tube A to 40 a discharge tube E, the path of movement being intercepted by the wheel B.

F is a guide for the coin when transferred by the plunger.

The arrangement thus far described is 45 such that each reciprocation of the plunger D will carry a coin discharged from the lower end of the tube A along the guide F and in so doing will engage said coin with one of the pockets C, causing the partial 50 rotation of the wheel B. This will operate a suitable register, not shown, which will count the coin so that the number passing through the machine is accurately tallied. If however, a smaller coin or one of a different dimension were in the tube A, it

would operate the counter in the same manner as the coin of the proper dimension, rendering the record inaccurate. To overcome the defect just described, I have provided a rejecting mechanism which prevents the 60 passage of an undersized coin beyond the wheel B or the turning of the latter thereby. I have further provided means by which such rejected coin may be ejected from the machine to render the counting mechanism 65 again operative.

The specific construction of locking mechanism preferably used comprises a pivotal dog G, which has a detent H for engagement with a series of locking shoulders I 70 on the wheel B. A portion of this dog forms a gage opposite the guide F and so spaced that a coin of the proper dimension or size when actuated by the plunger D will force the detent H of said dog out of engagement with the shoulder I and permit the rotation of the wheel B. If, on the other hand, the coin is undersized, the dog will not be moved sufficiently to disengage the 75 detent from the shoulder and consequently 80 rotation of the wheel B is effectually prevented. This will render the mechanism inoperative until the improper coin is removed.

In order that the dog G may be more 85 easily operated, it is preferable to provide a gradual cam surface thereon and at the same time it is necessary to provide clearance for the turning of the wheel in the unlocked position of said dog. I therefore 90 preferably provide the dog with a movable finger J, which is adjustable from a position where it clears the wheel during the rotation thereof to a position where it projects into one of the pockets C. In the latter 95 position, a gradual cam surface is presented by the edge K of the finger, along which the coin will be moved by the plunger D and which will unlock the dog by such movement. It will be understood that after the dog G is unlocked the coin must actuate the wheel B before disengagement from the cam—as otherwise the dog would be returned to its locking position. Thus, by 100 projecting the finger K into the pocket C, a better relative arrangement of the parts is obtained, while during the subsequent rotation of the wheel said finger is free to be moved outward where it will clear the 105 wheel.

When an undersized coin is fed by the plunger, the mechanism remains locked, while the coin is also held from further movement by the plunger. This would block the machine, and I have therefore provided an ejector by which the coin may be quickly removed. This preferably consists of a second reciprocatory bar L which is arranged beneath the plunger D and normally forms the bottom of the guideway, along which the coin is passed by said plunger. An aperture M is formed in this bar, which normally registers with the discharge tube E, so that any coin that passes the counting wheel will fall through the said aperture M into said tube. Whenever the mechanism is locked and a small coin is lodged in the guideway, the attendant may eject said coin by pushing inwardly the bar L until the aperture M registers with the coin and permits it to drop upon a lower guide surface N. The bar L is then subjected to a further inward motion, which will push the small coin forward until it drops through the discharge tube O, shown as in registration with tube A. A further function performed by the bar L is to return the plunger D to its normal position, which is accomplished by the engaging of end of bar L with a shoulder P upon the lower side of the plunger. Thus, by a simple operation of pushing inwardly the bar L, the false coin is ejected and the mechanism is rendered operative for the counting of the remaining coins.

Where the mechanism is applied to a power-driven machine, it is desirable to make provision for the stopping of the plunger D without straining or breaking any part of the actuating mechanism. Such a provision is diagrammatically illustrated in Fig. 1, in which Q is a pitman rod for actuating the plunger D and which is connected to a rotary crank R actuated by a belt drive S. The driving force of this belt is so adjusted that while sufficient to actuate the plunger under normal load, it will slip whenever the wheel B is locked and will not exert sufficient force to injure any part of the mechanism.

What I claim as my invention is:

1. The combination with an actuating member, of locking means for said member, means actuated only by a coin of proper size for releasing said locking means, said actuating member not being actuated by a coin not of proper size, and means for removing a coin from said member if said coin is not the proper size.
2. In a coin counting mechanism, an actuating member, means for locking said member, means for transferring a coin past said member, means actuated by a coin of proper size for unlocking said member, and means for removing the coin when not of proper size.

3. In a coin counting mechanism, the combination with a rotary member, of a plunger for transferring a coin past said member, means for locking said member from rotation, means actuated by a coin of proper size for unlocking said member, and a second plunger for removing the coin when not of proper size.

4. In a coin controlled apparatus, a coin feeding tube, a coin discharge tube, a guideway between said tubes, a member extending into said guideway, means for locking said member, means extending into said guideway and actuated by a coin of proper size for unlocking said member, a bar within said guideway for transferring a coin from said coin feeding tube to said coin discharge tube if said coin is of proper size, and a second bar normally forming the bottom of said guideway for removing said coin when not of the proper size.

5. In a coin controlled apparatus, the combination with an actuating member, of a member for transferring a coin of proper size past said actuating member, a second member for removing the coin when not of proper size, and a means for actuating said first-mentioned member from said second member.

6. In a coin counting mechanism, an actuating member having a projection extending into the path of the coin, a dog for locking said member from rotation, and a movable finger upon said dog adapted to be actuated by a coin of proper size to move said dog to unlock said actuating member, said finger being adjustable from a position where it clears said actuating member during the rotation thereof to a position where it lies adjacent to said projection.

7. In a coin counting mechanism, a rotary member provided with a pocket in the periphery thereof, a dog for locking said member from rotation, and a finger pivoted to said dog extending within said pocket and adapted to clear said rotary member during rotation thereof, said finger being adapted to actuate said dog to unlock said rotary member when actuated by a coin of proper size.

8. In a coin counting mechanism, an actuating member having a pocket in the periphery thereof, means adjacent said member for locking said member from rotation, and means upon said first-mentioned means extending within said pocket and adapted to clear said actuating member during movement thereof, said means upon the first-mentioned means being adapted to actuate said locking means to unlock said actuating member when actuated by a coin of proper size.

9. In a coin controlled mechanism, the combination with a rotary member extending into the path of the coin, of a plunger for transferring a coin in its path past said

actuating member, a second plunger for removing the coin, and a shoulder upon said first-mentioned plunger in the path of said second plunger for returning said first-mentioned plunger to its original position through said second plunger.

- 5 10. In a coin counting mechanism, a rotary member having a projection extending into the path of the coin to be actuated thereby,
10 a dog for locking said member from rota-

tion, a finger for releasing said dog movable into the path of said projection when actuated by said coin and adapted to clear said projection when released by the coin.

In testimony whereof I affix my signature 15 in presence of two witnesses.

FREDERICK N. ROSENSTENGEL.
